UNITED STATES PATENT OFFICE.

MILTON B. ROLLER, OF SAN FRANCISCO, CALIFORNIA, ASSIGNOR TO THOMAS DAY COMPANY, OF SAN FRANCISCO, CALIFORNIA, A CORPORATION OF CALIFORNIA.

DESIGN FOR AN ELECTRIC-LIGHTING BRACKET.

61,117.

Specification for Design. Patented June 20, 1922.

Application filed August 4, 1921. Serial No. 489,878. Term of patent 7 years.

To all whom it may concern:

Be it known that I, MILTON B. ROLLER, a citizen of the United States, and a resident of the city and county of San Francisco, State of California, have invented a new, original, and ornamental Design for an Electric-Lighting Bracket, of which the following is a specification, reference being had to the accompanying drawings, forming a part thereof.

In the drawings:

Fig. 1 is a front elevation showing conductor tubes in dotted lines.

Fig. 2 is an edge view or elevation showing the conductor tubes, light socket and bulb in dotted lines.

What is claimed is:

The ornamental design for an electric lighting bracket, substantially as shown.
MILTON B. ROLLER.
